UNITED STATES PATENT OFFICE.

EDGAR PECKHAM, OF ANTWERP, NEW YORK.

IMPROVEMENT IN APPARATUS FOR TREATING ORE AND MANUFACTURING IRON AND STEEL.

Specification forming part of Letters Patent No. 140,158, dated June 24, 1873; application filed May 9, 1873.

To all whom it may concern:

Be it known that I, EDGAR PECKHAM, of Antwerp, Jefferson county, New York, have invented certain Improvements in Furnaces for Desulphurizing and otherwise Treating Ores and Manufacturing Iron and Steel directly therefrom, of which the following is a specification:

The first part of my invention relates to the combination and arrangement of the chambers, retorts, and cooling-chambers in such a manner that each chamber, retort, and cooling-chamber forms one section, and can be operated alone and independent of the rest of the furnace. The second part of my invention relates to the combination and arrangement of two or more sections of chambers and retorts (each chamber and retort forming one section) in such a manner that the furnace can be constructed with any desired number of sections. The third part relates to a combination and arrangement of two or more sections of chambers, retorts, and cooling vats or chambers lengthwise, (each chamber, retort, and cooling-chamber forming one section,) in such a manner that the furnace can be constructed with any desired number of sections.

Figure 1, a side elevation; Fig. 2, transverse section on line *x x* in Fig. 1; Fig. 3, a longitudinal section.

A A represent the walls, which may be of brick or other suitable material. B is the fire, which may be of any of the usual forms for burning wood or coal. C is the horizontal draft or flame and heat passage from the fire B, and C' is the passage in the end wall of the furnace for conveying the flame and heat from the passage C to the chambers D, D¹, and D². The heat and flame pass from the fire B through the passage C, and from C through C' to the chambers D, D¹, and D², and through D, D¹, and D² to the stack E, passing under and over the retorts F, F¹, and F². Thus, the upper and lower sides of each retort are exposed to the full heat and flame from the fire B, and the flame traverses the interior of the ore-chambers D, D¹, and D². By a proper regulation of the dampers G and G¹ the passage C, the chambers D, D¹, and D², and the retorts F, F¹, and F², can be kept at a cherry-red heat. H, H¹, and H² are hoppers or openings with

slide-covers in the top of the furnace, through which the ore is charged into the chambers D, D¹, and D². I, I¹, and I² are openings (with covers) in the bottom of the chambers D, D¹, and D², through which the ore is transferred from chambers D, D¹, and D² to retorts F, F¹, and F². The openings are kept closed except when transferring ore. K, K¹, and K² are passages for transferring the ore from retorts F, F¹, and F² to cooling vats or chambers L, L¹, and L². M, M¹, and M² are dampers for closing said passages, and are kept closed except when the ore is being transferred from retorts to cooling-chambers. The ore in the chambers D, D¹, and D² is stirred and operated through the doors O, O¹, and O². The doors Q, Q¹, and Q² in the side of the passage C are to remove any ashes or emery that may accumulate in the passage. The door R in the end wall of furnace is to admit cold air into the chambers D, D¹, and D² when treating ores containing sulphur. The blast-pipe S is for conveying wind from the blowers to passage C, when required. T is a reducing fire or furnace, which may be of any of the usual forms of reducing fires, or furnaces for reducing ores. U is a damper to the reducing-furnace T. V is an opening or passage for conveying the heat or flame from the reducing-furnace T to the converting-furnace A A. W is a slide-damper for closing the passage V when reducing-furnace is not in operation.

The manner of conducting the process and operating the furnace is as follows, viz: The ore is first reduced to about the size of small walnuts, (it may be a little larger or smaller,) and if it contains any dirt or stony matter it should be separated from them, and then mixed with about an equal quantity in bulk of fine charcoal, coke, or bituminous coal, (fine charcoal preferred.) Fire is then made in the fireplace B, of coal or wood, and the dampers G and G¹ opened, and all the other doors and dampers closed. When the passage C and chambers D, D¹, and D² are heated to a cherry-red heat, the chambers D, D¹, and D² are charged with ore through the hoppers or openings H, H¹, and H² to the depth of from four to six inches. The ore, while in chambers D, D¹, and D², should be frequently stirred or rabbled by operating through the

doors U, U, U¹ U¹, and U² and U², after being in chambers D, D¹, and D² about twenty-four hours, or sufficient time to become heated throughout to a cherry-red. It is then transferred, through openings I, I¹, I² to retorts F, F¹, and F². After the ore has been transferred from chambers D, D¹, and D² to retorts F, F¹, and F² new charges of ore should be put in the chambers D, D¹, and D². After the ore has been in retorts F, F¹, and F² sufficient time to remove the oxygen and reduce it to a metallic state, (which can be determined by sampling it through doors O, O¹, and O²—the time required will depend upon the character of ore employed, and will vary from three to six days for a complete reduction,) it is then transferred from retorts F, F¹, and F², through openings or passages K, K¹, and K², to cooling vats or chambers L, L¹, and L², where it is allowed to cool before using. After the ore has been transferred from retorts F, F¹, and F² to cooling vats or chambers L, L¹, and L² the dampers M, M¹, and M² to passages K, K¹, and K² should be closed, and the ore in chambers D, D¹, and D² should be transferred, through openings I, I¹, and I², to retorts F, F¹, and F², and new charges of ore put in chambers D, D¹, and D². When the ore in the cooling vats or chambers L, L¹, and L² is cold it is ready for use, and may be removed to the reducing fire or furnace, and the ore from the retorts F, F¹, and F² transferred to cooling-chambers L, L¹, and L², and the ore from chambers D, D¹, and D² to retorts F, F¹, and F², and new charges of ore put in chambers D, D¹, and D². The doors O, O¹, and O² to retorts F, F¹, and F², and the doors P, P¹, and P² to cooling-vats L, L¹, and L² should be kept air-tight by plastering the edges so as to prevent the admission of any cold air.

The process may be slightly varied, as follows: As soon as the ore in the chambers D, D¹, and D² has been sufficiently treated it may be transferred to retorts F, F¹, F², and new charges of ore put in the chambers D, D¹, and D², and as soon as they have been also sufficiently treated they may be also transferred to retorts F, F¹, and F², and new charges of ore put in chambers D, D¹, and D². The remainder of the process is conducted as previously described.

In this way the retorts and cooling vats or chambers will contain double charges, and twice as much ore as when charged and conducted in the manner previously described, thereby enlarging the capacity of the furnace.

If it is desired to carbonize the ore more thoroughly, so as to produce a higher steel, or steel containing a greater percentage of carbon, fresh fine charcoal should be added to and mixed with the ore when it is transferred from chambers D, D¹, and D² to retorts F, F¹, and F².

When treating ores containing sulphur, the door R should be opened sufficiently to allow a free admission of cold air to the chambers D, D¹, and D², but not enough to reduce the temperature of the chambers below a cherry-red, care being taken to keep the chambers at a

cherry-red heat. The ore should be stirred or rabbled frequently.

The furnace can be operated without using the cooling vats or chambers by allowing the ore to cool on the ground, or using it hot direct from the retorts. It is preferable to use the cooling-vats, and allow the ore to cool in them before using, as by cooling in this manner the ore is annealed, and produces very tough iron and steel.

By constructing the furnace in sections, each chamber, retort, and cooling vat or chamber forming one section, the sections may be used alternately, and the process made a continuous one. The furnace can be constructed with any given number of sections, and its capacity increased or diminished, as desired.

When working rich magnetic ores, that work dry, because they do not produce cinder enough, or that produce a thick, heavy, impure cinder, that will not flow readily, I use as a flux lean hematite ore or limestone in the following manner, viz: I reduce the ore or limestone by stamping or crushing to about the size of coarse shot, and mix it with the ore before charging into the furnace, using from one-sixth to one-tenth as much flux in bulk as I do ore, varying the amount used according to the richness and character of the ore employed; using enough of the flux to produce a thin liquid cinder that will flow readily.

When manufacturing iron and steel from the prepared ore, fire is made in the reducing fire or furnace T—which may be of any of the usual forms of reducing fires or furnaces—and the waste heat or flame therefrom used to heat the converting-furnace A A. The converting-furnace is operated substantially as previously described; and the ore, when sufficiently reduced, is taken from the cooling vats or chambers L, L¹, and L² to the reducing fire or furnace T, and there manipulated into iron and steel in the usual manner.

I claim—

1. The combination of the chambers D, D¹, and D², one or more, the retorts F, F¹, and F², and the cooling vats or chambers L, L¹, and L², each chamber, retort, and cooling-chamber forming one section, constructed substantially as and for the purposes hereinbefore set forth.

2. The combination of two or more sections of chambers and retorts lengthwise, each chamber and retort forming one section, constructed substantially as and for the purposes hereinbefore set forth.

3. The combination of two or more sections of chambers, retorts, and cooling-chambers lengthwise, each chamber, retort, and cooling-chamber forming one section, constructed substantially as and for the purposes hereinbefore set forth.

Dated April 17, 1873.

EDGAR PECKHAM.
